UNITED STATES PATENT OFFICE.

JAMES P. MOSIER, OF ST. FRANCOIS, MISSOURI, ASSIGNOR, BY DIRECT AND MESNE ASSIGNMENTS, TO NATIONAL LEAD COMPANY, OF NEW YORK, N. Y., A CORPORATION OF NEW JERSEY.

COMBINED MATERIAL REMOVING AND CONVEYING MACHINE.

Application filed May 9, 1921. Serial No. 467,819.

To all whom it may concern:

Be it known that I, JAMES P. MOSIER, a citizen of the United States, and a resident of the city of St. Francois, in the county of St. Francois and State of Missouri, have invented a new and useful Improvement in Combined Material Removing and Conveying Machines, of which the following is a specification.

10 This invention relates to machines for removing and conveying materials, such as ore, coal and the like, wherein the material is removed from the pile by means of a scoop and is then transferred to an endless 15 rotary conveyer which delivers the material to the point of discharge. One of the principal objects of the present invention is to utilize the scoop support, usually a boom, as a chute for delivering the material from 20 the scoop to the endless conveyer. Another object is to utilize the forward movement of the machine for forcing the scoop into the material and thereby dispense with the mechanism commonly used for movably 25 supporting the scoop and forcing the same into the material. Another object is to utilize the mechanism which lifts the boom and scoop as a means for dumping the scoop and swinging the boom laterally. Another 30 object is to produce a small and compact self propelled machine of light weight and of simple construction which can be readily moved about a mine and can be operated by a single attendant.

35 The invention consists principally in an arrangement of parts whereby the boom that carries the scoop serves also as a chute for the material delivered thereto from said scoop; it also consists in an arrangement 40 whereby the boom that carries the scoop serves also to deliver the material from the scoop to the conveyer; it also consists in mounting the scoop on the end of the boom and adapting it to dump its contents onto 45 said boom; it also consists in a single means for rotating the scoop and swinging the boom sidewise and vertically; and it also consists in the parts and combinations and arrangements of parts hereinafter described 50 and claimed.

In the accompanying drawings, which form part of this specification, and wherein like symbols refer to like parts wherever they occur,

Fig. 1 is a plan view of a material removing and conveying machine embodying my invention;

Fig. 2 is a side elevation of said machine;

Fig. 3 is a vertical central longitudinal section through the machine on the line 60 3-3 in Fig. 1;

Fig. 4 is an enlarged plan view of the inner end of the boom and a portion of the supporting frame therefor, showing the manner of pivotally securing said boom to 65 said frame;

Fig. 5 is a vertical section on the line 5-5 in Fig. 4;

Fig. 6 is a vertical cross-section through the machine on the line 6-6 in Fig. 3;

Fig. 7 is an enlarged axial section through 70 the mechanism for propelling the machine;

Fig. 8 is a transverse section through the boom on the line 8-8 in Fig. 1;

Fig. 9 is an enlarged axial section through 75 the mechanism for raising and swinging the boom; and

Fig. 10 is a perspective view showing the brake mechanism used in connection with the mechanism for propelling the machine. 80

The machine shown in the accompanying drawings comprises a rigid body portion 1 supported on axles 2 to which are fixed flanged car wheels 3 supported on rails 4. Heavy springs 5 are interposed between the 85 body 1 and the axles 2 as in the ordinary locomotive truck. Attached to the rear of the wheeled body 1, by means of a coupling member 6, is an ordinary mine car 7.

Mounted on a casting 8 at the front end 90 of the body 1 is a boom 9. The cross-sectional shape of the boom is of H-shape and has a hinge-pin 10 disposed crosswise of its inner end and supported therefrom by means of hinge straps 11. These hinge- 95 straps 11 are riveted to the underside of the web portion of the boom adjacent to the side margins thereof and have eye portions adapted to receive the ends of the hinge-pin 10. The portion of the hinge-pin 10 between the spaced straps 11 is journaled in the eye portion of a hinge-strap 12. The hinge-strap 12 rests on the upper surface of a plate 13, whose inner end portion rests on the upper surface of the end casting 8. 100 The plate 13 extends forward of the end casting 8 and its outer end is suitably supported by means of a brace member 14. A 105

pivot-pin 15 extends through alined openings in the hinge-strap 12, the plate 13 and the upper flange of the end casting 8, and is held in position by means of cotter pins. 5 In consequence of the above arrangement, the boom is permitted to swing vertically about the hinge-pin 10 and is permitted to swing horizontally about the pivot-pin 15, and said plate 13 limits the downward 10 movement of said boom and affords support therefor during the digging action.

Located at the outer end of the boom is a scoop or bucket 16, whose front and top portions are open. The scoop is provided 15 on opposite sides with oppositely disposed rearwardly projecting lugs 17 which are pivotally secured to the adjacent side flanges of the boom, below the web portion thereof, by means of pivot-bolts 18. The bottom 20 of the scoop is provided along its front end with digger teeth 19; and the back of said scoop, in the normal or lowermost position thereof, bears against the outer end of a stop-bar 20, which projects from the 25 under side of the boom, whereby said scoop is supported from said boom with its digger teeth clear of the ground.

The scoop is swung about the pivot bolts 18 and the boom is swung both vertically 30 and horizontally by means of chains 21 and 22. The chain 21 is secured to the upper corner of one side of the scoop and is used for swinging the boom in one direction; and the chain 22 is secured to the other 35 upper corner of the opposite side of the scoop and is used for swinging the boom in the opposite direction. Each of these chains passes between a pair of horizontally journaled guide rollers 23 mounted on an upright frame 24 at the front end of the body 1. The chains 21 and 22 also run over horizontally journaled guide rollers 25 which are also supported on the upright 40 frame 24, and thence onto winding drums 26 and 27 of the so-called planetary type. The drums 26 and 27 are loosely journaled 45 on a shaft 28, which is permanently geared to the driving shaft 29 of an electric motor 30 by means of a sprocket chain 31, whereby 50 said shaft rotates continuously.

Extending lengthwise of the body 1 is an 55 endless belt conveyer 32, which inclines rearwardly and upwardly from a point adjacent to the inner end of the boom to a point overhanging the mine car 7. The conveyer belt is driven in a direction which will cause the upper stretch thereof to travel rearwardly in the direction of the mine car 7 by means of a driving drum 33. This 60 driving drum 33 is located at the forward end of the conveyer and is fixed to a shaft 34, whose ends are journaled in suitable bearings in the opposite sides of the wheeled body. The upper end of the conveyer belt 65 is supported on an idler roller 35 whose end

portions are journaled in the bearing-blocks 36 of suitable belt-tighteners 37. These belt tighteners are secured to the side rails 38 of the conveyer, which rails, in turn, are secured to the wheeled body 1. The upper 70 stretch of the conveyer belt is supported at intervals throughout its length by means of idler rollers 39 whose opposite ends are journaled in the side rails 38.

The continuously rotating shaft 28, which 75 supports the winding drums 26 and 27, is permanently geared to a shaft 40 disposed between the axles 2 by means of a sprocket chain 41. The shaft 40 is permanently 80 geared to the driving drum 33 of the conveyer by means of a sprocket chain 42. The shaft 40 is adapted to be geared to the rear axle to propel the machine forwards or backwards by means of a planetary transmission gearing. Said gearing comprises a 85 driving sprocket 43 loosely journaled on the shaft 40 and connected to a sprocket on the rear axle by means of a sprocket chain 44 and said rear axle is permanently geared 90 to the front axle by means of a sprocket chain 45. The drive sprocket 43 is formed on one side with an internal gear 46 and has a flange on its opposite side provided with studs on which are journaled one or 95 more pinions 47, which mesh with a pinion 48 fixed to the shaft 40.

Loosely journaled on the shaft 40 on each side of the drive sprocket 43 are grooved 100 wheels 49 and 50. The grooved wheel 49 has one or more pinions 51 journaled on 105 studs which project from one side thereof, which pinions mesh with the internal gear 46 of the drive sprocket 43 and a pinion 52 fixed to the shaft 40. The grooved wheel 50 is located on the opposite side of the 110 drive sprocket 43 and is provided with an internal gear 53 which meshes with the pinions 47 on said drive sprocket. The grooved periphery of the wheel 49 is encircled by 115 a contracting friction brake band 57. This friction band is tightened by means of an eccentric keyed to a rock rod 55 which is provided with a foot lever 56. Manipulation 120 of the foot lever 56 tightens the brake band 57, which action holds the wheel 49 against rotation and thereby forces the drive sprocket 43 to rotate in a direction which will drive the machine forward.

The grooved periphery of the wheel 49 125 is encircled by a contracting friction brake band 54. This friction band is tightened by means of an eccentric keyed to a rock sleeve 58 journaled on the rock rod 55 and is provided with a foot lever 59 located adjacent to the foot lever 56. Manipulation 130 of the lever 59 tightens the brake band 54, thus holding the wheel 50 against rotation and thereby forcing the drive sprocket 43 to rotate in a direction that will drive the machine rearward.

The winding drums 26 and 27 are driven from the shaft 28 by means of planetary gearing in a manner similar to the drive sprocket 43. The planetary gearing for the drums 26 and 27 comprises two pinions, 28^a, one for each drum, which are fixed to the shaft 28 and mesh with one or more pinions 60^a and 61^a journaled on studs on groove wheels 60 and 61. These grooved 10 wheels 60 and 61 are loosely journaled on the shaft 28 with their pinions meshing with the internal gear rings 26^a and 27^a formed in driving drums 26 and 27. The peripheral portions of the respective 15 grooved wheels 60 and 61 are encircled by contracting friction bands 62 and 63 similar to the brake bands 54 and 57. The friction band 62 is tightened to lock the wheel 60 to the shaft 28 by means of an eccentric keyed to a rock shaft 64 which is provided with an operating lever 65; and the friction band 62 is tightened to lock the wheel 61 to said shaft 28 by means of an eccentric keyed to a rock sleeve 66, which 20 is journaled on said rock shaft 64 and is provided with an operating lever 67 located adjacent to the operating lever 65.

Assuming that the machine, with the mine car coupled to the wheeled body thereof 30 and with the lower end of the scoop in the position indicated in full lines in Fig. 2, has been self propelled along the mine track to bring the scoop close to the loose material to be loaded, the operation of the machine is as follows:

The motor 30 having been started, it will, of course, be evident, by reason of the respective sprocket chain connections 31, 41 and 42 between the continuously operating 40 motor shaft 29, and the driving drum 33 of the conveyer 32, that the conveyer belt will be in continuous operation with its upper stretch moving toward the rear of the machine. The operator, standing on a platform 45 68 so as to be within easy reach of the hand levers 65 and 67 and the foot levers 56 and 59, then manipulates the foot lever 56 to propel the wheeled body 1 forward, thereby forcing the scoop into the bottom 50 of the pile of loose ore. During this forward movement of the machine, the hand levers 65 and 67 are manipulated to cause the scoop to swing upwardly thus skimming its charge from the side of the pile. The 55 scoop having been filled, the upward swinging movement thereof is continued until the back of the scoop rests upon the upper surface of the web portion of the boom. The operator continues to manipulate the hand levers 65 and 67, whereby the drums 26 and 27 continue to move in a winding direction and the continued pull on the scoop causes said boom to swing upwardly.

This upward swinging movement of the 60 boom causes the material to slide out of the

scoop onto the upper channel of the boom, which functions as a chute and delivers the material to the rearwardly moving upper stretch of the conveyer belt. The material is then carried to the delivery end of the 70 conveyer where it is discharged into the mine car coupled to the rear of the machine. This operation of filling the scoop and elevating the boom, to cause the contents of the scoop to slide down the boom onto the 75 conveyer and be delivered to the mine car, is continued until said car has been filled, whereupon the loaded car is replaced with an empty one.

The boom is swung to-and-fro, to enable 80 a pile of ore to be removed from either side of the machine, by means of the chains 21 and 22, which are used for swinging the scoop over the boom and for raising said 85 boom.

These chains are secured to the scoop on opposite sides thereof and are wound around separate winding drums. Thus, when it is desired to swing the boom towards the side of the machine on which 90 the operator stands, the operator manipulates the hand lever 65, whereby the drum 26 is rotated in a winding direction and the chain 21 attached to the operating side of the scoop is wound on said drum, thereby 95 causing the boom to swing both vertically and horizontally. When it is desired to swing the boom to the other side of the machine, the lever 67 is manipulated, whereby the pull is on the opposite side of the 100 scoop thus causing the boom to be raised and swung away from the operator.

When both levers 65 and 67 are simultaneously operated, the pull on the opposite sides of the scoop is equal and the boom is 105 caused to rise without lateral movement.

The boom may be held in its elevated position a length of time sufficient to enable the contents of the scoop to reach the conveyer by a slip pressure of the respective 110 brake bands 54 and 57 on grooved wheels 49 and 50. This slip pressure may also be used to control the lowering movement of the boom whereby the same may be lowered 115 without shock.

Obviously, the hereinbefore described machine admits of considerable modification without departing from the invention; therefore, I do not wish to be limited to the 120 exact details of construction shown and described.

What I claim is:

1. In a self-propelled wheeled loading machine wherein the digging action of the 125 scoop is effected by the bodily movement of the machine, a conveyer, a rigid boom pivotally mounted near one end of said conveyer, and a scoop pivotally mounted on the end of said boom, said scoop being adapted to deliver its contents onto said boom and said 130

boom being arranged to deliver same onto said conveyer.

2. In a self-propelled wheeled loading machine wherein the digging action of the scoop is effected by the bodily movement of the machine, a vertically swinging integral boom, of such cross sectional shape as to adapt it to serve as a chute and a material gathering device mounted on said boom and adapted to deliver its contents onto said boom, said boom being immovable endwise independently of the body.

3. A self-propelled wheeled loading machine wherein the digging action of the scoop is effected by the bodily movement of the machine comprising a conveyer and a rigid boom pivotally mounted at the receiving end of said conveyer to swing vertically, a scoop pivotally mounted on the outer end 20 of said boom to swing on a horizontal axis and means for raising said boom to cause the contents of said scoop to slide down said boom onto said conveyer.

4. A self-propelled wheeled loading machine wherein the digging action of the scoop is effected by the bodily movement of the machine comprising a conveyer whose receiving end is close to the ground and a channelled boom pivotally mounted at the receiving end of said conveyer to swing vertically, a scoop pivotally mounted on the outer end of said boom to swing vertically, and means for swinging said scoop into position to deliver its contents onto the upper surface of said boom and for raising said boom, said boom in its raised position constituting a chute for delivering the contents of said scoop to said conveyer.

5. A self-propelled wheeled loading machine wherein the digging action of the scoop is effected by the bodily movement of the machine comprising a conveyer which inclines upwardly from a point close to the ground at the receiving end and a rigid boom of H-section pivotally mounted at the receiving end of said conveyer to swing vertically and sidewise, a scoop pivotally mounted on the free end of said boom, to swing vertically, and means for swinging said scoop to fill the same and to bring it into position to deliver its contents onto the upper surface of the boom, said scoop swinging means also constituting a means for lifting the boom, whereby the contents of the scoop are caused to slide along said boom from the scoop to the receiving end of the conveyer, and a means for swinging said boom sideways.

6. A self-propelled loading machine wherein the digging action of the scoop is effected by the bodily movement of the machine comprising a wheeled truck, a conveyer mounted on said truck with its front end below the top of said truck, and a rigid channelled boom pivotally mounted at the

receiving end of said conveyer to swing vertically, a scoop pivotally mounted on the outer end of said boom to swing vertically and having a discharge end, and means for swinging said scoop upwardly to fill the same and to bring the discharge end thereof into position over the boom, said scoop swinging means constituting also a means for lifting said boom, which action causes the contents of the scoop to slide out of said scoop onto the boom and along said boom to the receiving end of the conveyer.

7. A self-propelled loading machine wherein the digging action of the scoop is effected by the bodily movement of the machine comprising a wheeled body and a car adapted to be coupled to the rear end of said body, an endless conveyer supported on said body and disposed with its receiving end close to the ground at the front of said body and its delivering end at the rear end thereof and overhanging said car, a boom pivotally mounted on the forward end of said body adjacent to the receiving end of said conveyer to swing vertically, a scoop mounted on the free end of said boom, means for propelling said body forward to force said scoop into the material, and means for lifting said boom to cause the contents of said scoop to slide along said boom from the scoop directly onto the receiving end of the conveyer, which conveyer, in turn, delivers the material to said car.

8. A self-propelled wheeled loading machine wherein the digging action of the scoop is effected by the bodily movement of the machine comprising a body portion, a boom pivotally mounted on said body portion to swing vertically and sidewise, and winding mechanism mounted on said body portion for swinging said boom vertically and sidewise, said winding mechanism comprising separate chains attached to the free end of said boom on opposite sides thereof and arranged for independent or simultaneous operation.

9. A self-propelled wheeled loading machine wherein the digging action of the scoop is effected by the bodily movement of the machine comprising a conveyer that inclines upwardly from its receiving end to its delivering end and a channelled boom pivotally mounted at the receiving end of said conveyer to swing vertically and sidewise, a scoop mounted on the free end of said boom, and means for swinging said boom vertically and sidewise, said means comprising separate chains operatively connected to the opposite sides of said scoop and arranged for independent or simultaneous operation.

10. A loading machine comprising a wheeled body, a conveyer mounted thereon, a boom pivotally mounted on said body adjacent to the receiving end of said conveyer to swing vertically and sidewise, a

- scoop pivotally mounted on the free end of said boom to swing vertically, and means for swinging said scoop to bring the same into a position to deliver its contents onto the upper surface of the boom, for swinging the boom upwardly to cause the contents of said scoop to slide along said boom from the scoop to the receiving end of the conveyer, and for swinging the boom sidewise to engage material located on either side of the machine, said means comprising separate chains operatively connected to said scoop on opposite sides thereof and arranged for independent or simultaneous operation.
11. A loading machine comprising a wheeled body, an endless conveyer mounted thereon, means for continuously operating said conveyer, means for propelling said wheeled body forward and rearward, means for connecting said propelling means to the conveyer operating means at the will of the operator, a boom pivotally mounted on said body to swing vertically and sidewise, said boom having a channel formed in its upper surface and extending longitudinally of said boom, a scoop pivotally mounted on the free end of said boom to swing vertically, and a hoisting means on said body comprising a chain operatively connected to one side of said scoop and a chain operatively connected to the other side of said scoop, said chains being connected to winding drums adapted to be independently or simultaneously connected to the continuously operating conveyer operating means, whereby both of said drums may be actuated to swing the scoop into position to deliver its contents onto the channel formed in the upper surface of said boom and the boom swung upwardly to cause the contents of said scoop to slide along said channel from the scoop to the receiving end of said conveyer, or one of said drums may be actuated to lift and swing said boom to either side of the machine.
12. A self-propelled loading machine wherein the digging action of the scoop is effected by the bodily movement of the machine comprising a wheeled body, a conveyer that is mounted on said body and inclines upwardly from a point near the ground at its front end, and a channeled boom pivotally mounted on said body above the receiving end of said conveyer to swing vertically, a scoop pivotally mounted on the free end of said boom, and propelling means for said wheeled body, whereby said wheeled body may be moved forward to force the scoop into the material.
13. A self-propelled loading machine 60 wherein the digging action of the scoop is effected by the bodily movement of the machine comprising a wheeled body, a boom pivotally mounted on said body to swing vertically and sidewise, a scoop pivotally mounted on the free end of said boom to swing vertically, propelling means for said wheeled body, whereby said wheeled body may be moved forward to force the scoop into the material, and a stop member mounted on said boom and adapted to engage said scoop to prevent rearward swinging movement thereof while said scoop is being forced into the material.
14. A self-propelled loading machine 75 wherein the digging action of the scoop is effected by the bodily movement of the machine comprising a wheeled body, a conveyer mounted on said body and inclining upwardly from receiving end to discharge end thereof, a boom of H-section pivotally mounted on said body above the receiving end of said conveyer to swing vertically, a scoop mounted on the free end of said boom, propelling means for said body whereby said body may be moved forward to force the scoop into the material, and means for raising said boom to cause the contents of said scoop to slide out of said scoop onto the boom and be delivered thereby to the 90 conveyer.
15. A self-propelled loading machine 95 wherein the digging action of the scoop is effected by the bodily movement of the machine comprising a wheeled body, a conveyer mounted on said body inclining upwardly from receiving end to discharge end thereof, a boom of H-section pivotally mounted on said body above the receiving end of said conveyer to swing vertically, means for supporting said boom in its lowermost position, a scoop mounted on the free end of said boom, propelling means for said body whereby said body may be moved forward to force the scoop into the material, and means for raising said boom to cause the contents of said scoop to slide out of said scoop onto the boom and be delivered thereby to the 105 conveyer.

Signed at St. Francois, Missouri, this 6th day of May, 1921.

JAMES P. MOSIER.
